UNITED STATES PATENT OFFICE

HENRY G. DIBELKA, OF CHICAGO, ILLINOIS, ASSIGNOR TO THE KINGSLEY-MILLER COMPANY, OF CHICAGO, ILLINOIS, A CORPORATION OF ILLINOIS

DESIGN FOR A VEHICLE WHEEL HUB CAP

Application filed July 15, 1929. Serial No. 32,051. Term of patent 3½ years.

To all whom it may concern:

Be it known that I, HENRY G. DIBELKA, a citizen of the United States, residing at Chicago, in the county of Cook, State of Illinois, have invented a new, original, and ornamental Design for Vehicle Wheel Hub Plates, of which the following is a specification, reference being had to the accompanying drawing, forming a part thereof.

In this drawing:

Figure 1 is a face view of the vehicle-wheel hub plate showing my new design; and Figure 2 is an edge view of the same.

I claim:

The ornamental design for a vehicle-wheel hub plate as shown.

In witness whereof I have hereunto set my hand.

HENRY G. DIBELKA.
